UNITED STATES PATENT OFFICE.

CHARLES B. MOORE, OF EVANSTON, ILLINOIS, ASSIGNOR, BY MESNE ASSIGNMENTS, TO AMERICAN ARCH COMPANY, OF NEW YORK, N. Y., A CORPORATION OF DELAWARE.

LOCOMOTIVE-FURNACE.

1,136,037.

Specification of Letters Patent.

Patented May 4, 1915.

Application filed February 14, 1912. Serial No. 677,561.

To all whom it may concern:

Be it known that I, CHARLES B. MOORE, a citizen of the United States, and a resident of the city of Evanston, county of Cook, 5 and State of Illinois, have invented certain new and useful Improvements in Locomotive-Furnaces, of which the following is a specification.

My invention relates to improvements in locomotive boiler furnaces and has particular reference to a novel system for building and maintaining baffles or walls within the fireboxes of locomotives which baffles or walls are commonly called arches.

15 The general objects of my invention is to provide a standard arch construction which can with equal facility be used for the building of arches in narrow, medium and wide fireboxes and which arches can be easily and 20 quickly installed; which arches shall be of relatively light weight and low cost; which arches shall be easy to repair and parts of which can be readily removed to give free access to the side sheets and flue sheet of the 25 firebox for repairs thereto, and which arches shall be of a form that shall materially assist in the admixing and commingling of the firebox gases, and thereby enhance the combustion of the fuel.

30 Further objects, features and functions of my invention appear hereinafter.

My invention consists of a system of arch construction by means of which arches having the above characteristics can be produced.

35 My invention further consists in a locomotive firebox arch comprising a plurality of similar arch bricks formed for mutual interlocking engagement and adapted to be supported either upon arch tubes or upon the side sheets of the firebox, the arch corresponding in width with the width of the firebox.

40 My invention further consists in an arch brick of such form and dimensions that it is adapted to combine with a number of bricks of substantially identical form, to produce arches in locomotive boiler fireboxes having different dimensions.

45 My invention further consists in the various novel arrangements, features of construction and combinations of parts by which the objects hereinabove outlined are attained, together with others which will 50 appear hereinafter, and all as fully de-

scribed with reference to the accompanying drawings, and as particularly pointed out in the appended claims.

In said drawings, which form a part of this specification, I have illustrated the application of my novel principle of arch building to the building of arches in locomotive boiler fireboxes of many different dimensions, and: Figure 1 is a central, longitudinal section of a locomotive boiler firebox having a front arch therein built in accordance with my invention; Fig. 2 is a horizontal section of the firebox on line 2—2 of Fig. 1; Fig. 3 is a vertical, transverse section of the firebox on line 3—3 of Fig. 1; Fig. 4 is an enlarged perspective view of my novel arch brick; Fig. 5 is an enlarged transverse section on line 5—5 of Fig. 2; Fig. 6 is a section similar to Fig. 5 showing a different arrangement of tubes. Fig. 7 is a figure similar to Fig. 5 showing the application of my arch to a locomotive firebox of the narrow type; Fig. 8 is a top plan view of the arch illustrated in Fig. 5; Fig. 9 is a top plan view of the arch illustrated in Fig. 6; Fig. 10 is a top plan view of the arch illustrated in Fig. 7.

55 My invention is capable of application to the building of arches in locomotive boiler fireboxes which occupy various positions and have different functions, and although I have confined the illustration to so-called front arches it should be understood that my invention is not thus limited.

On account of the rapid deterioration to 60 which locomotive firebox arches are subject by reason of the high temperature of the fire, the strong draft and the jarring effect of the locomotive when running on the road, it is necessary that they be so constructed 65 that they can be easily and quickly repaired. Furthermore, it is desirable that the arch be so constructed that the damaged portions or parts can be replaced by new bricks without disturbing or destroying the 70 parts of the arch which do not require repairing.

A particularly valuable feature of my invention resides in the fact that any portion of the arch or any individual brick of 75 the arch can be removed without disturbing the main body of the arch and a new brick or portion can be placed in position to complete the arch.

80 As shown in the drawings, a locomotive

firebox is made up of a flue sheet 2, side sheets 3-3, a crown sheet 4 and a rear sheet 5. The firebox is located within the boiler shell 6 and is provided with a fuel door or opening 7 at its rear end and flues 8 laid forward from the flue sheet. The firebox contains the usual grate 9. The firebox illustrated in Figs. 1, 2 and 3 is provided with an inclined water circulating tube 10 which 10 inclines upwardly and rearwardly from the lower portion of the flue sheet to the upper portion of the rear sheet and serves to increase the circulation of water between the front and rear water legs of the boiler.

15 A so-called front arch usually occupies an inclined position in the firebox extending from side sheet to side sheet therein and having its forward end in abutment with or arranged close to the flue sheet. The functions of these arches are to serve as a baffle to prevent the direct flow of the gases of combustion from the fuel bed to the flues and cause them to circulate back and forth through the firebox for the purpose of causing an even distribution of the heat to the whole interior of the firebox; further, to aid in the perfect combustion of the fuel by causing the various gases of combustion to be thoroughly and completely intermixed 25 as they rise through the firebox and incidentally to retain the gases in the firebox a sufficient time to completely oxidize all of the fuel particles. A further feature of these arches is to aid in maintaining complete combustion by giving off some of their absorbed heat at the times when the temperature of the gases of combustion drops below the ignition point. All of these desirable features are retained in arches built 30 in accordance with my novel method.

40 In carrying out my system I provide bricks A of substantially standard form which consist in substantially rectangular flat bricks having such dimensions that they will not be so heavy but that they can readily be placed in position in the firebox and being limited in size by the feature that they shall not be too large to be readily passed through the firebox door into the firebox.

45 Each of these bricks is provided upon one longitudinal edge with a groove or socket B adapting it to fit and rest upon the upper side of the arch or circulating tube 10. The opposite edge of the brick is provided with a half tongue C and a complementary half groove D whereby it is adapted to mutually interlock with a companion brick when the two bricks i.e. relatively reversed in position. One of the side faces of the brick is 50 provided with a relatively large shallow cavity or depression E which serves not only to lighten the brick without materially reducing its strength or its power to resist abrasion, but serving also to provide the arch with a plurality of subsidiary gas-mix-

ing pockets and variously angularly positioned gas-deflecting walls or baffles.

In applying my system to the building of arches in fireboxes, I arrange the circulating tubes longitudinally within the firebox in such a manner that the transverse distance between the tubes themselves or between the tubes and the side sheets is practically of substantially standard width, so that a single brick will span two adjacent supports 70 or be supported thereby, or of such a width that two bricks can rest upon two adjacent supports and span the space between them, the bricks being placed in oppositely inclined positions resting at their lower ends 75 upon the supports and abutting at their upper ends, the bricks being formed as described to mutually interlock at their abutting ends. As the bricks of the arch are supported in transversely inclined positions, 80 it is obvious that the spaces between the supports can vary to some extent from standard dimensions without necessitating the use of more than one form of brick of standard size. In boilers wherein the space between 85 the water-circulating tube and the adjacent side sheet is too great to be spanned by a single brick in an inclined position with its lower end resting upon the tube and its upper end leaning against the side sheet, I 90 span the space, as shown in Fig. 2, with two of the standard bricks, one resting at its lower end upon the water circulating tube and the other resting at its lower end upon lugs 11 suitably secured to the side sheet. 95 In narrow boilers, as shown in Figs. 7 and 10, I provide a single water circulating or arch-supporting tube and support the arch thereon, the arch bricks resting at their lower ends upon the tube and leaning against 100 the side sheets of the firebox.

In installing arches in fireboxes, as illustrated in Fig. 2, in accordance with my method, I place one of the bricks upon the lower end of the arch tube adjacent the 110 flue sheet inclining the brick outwardly and supporting it in position by means of a second brick resting at its lower end upon the lugs or studs 11 and the two bricks leaning against each other abutting substantially 115 midway the tube and the side sheet and mutually interlocked at their abutting ends. This lower portion of the arch is completed by two similar bricks placed transversely in line with the first two and supported by the circulating tube and the opposite side sheet. The abutting ends of these bricks rest against the flue sheet and their lower ends are spaced from the flue sheet on account of the inclined position of the tube upon which the arch rests. For the purpose of securely retaining the arch in its proper position upon the arch tube, I place a spacing brick 12 upon the lower end of the tube between 120 the first row of bricks and the flue sheet. 125

This spacing brick is grooved to fit the cylindrical surface of the tube and is retained in position by the pressure of the arch. The arch is completed by the addition, if necessary, of further transverse rows of bricks placed in position similar to the first row and extending from side sheet to side sheet.

A front arch usually extends rearwardly from the flue sheet to about the center portion of the firebox and from side sheet to side sheet. An arch thus positioned serves as a baffle to prevent the direct flow of the gases of combustion from the fuel bed to the flues and causes them to flow rearwardly in the firebox toward the rear sheet in order to escape around the upper end of the arch before they can flow forwardly to the flue sheet to escape through the flues. The gases are thus retained in the firebox a sufficient time to cause substantially complete combustion to take place therein before they escape from the firebox. Furthermore, as my arch is formed of what can be called transversely inclined leaves or panels, and as each of these panels is provided with a plurality of subsidiary pockets and walls arranged at various angles, it is seen that the gases strike the lower surface of the arch and different portions of the gaseous body are deflected at various angles and the gases of combustion are thoroughly intermingled and mixed.

The strong draft which is usually employed in locomotives tends to carry upward with the gases of combustion fuel particles and cinders which strike and flow upward along the under surface of the arch and tend to scour or wear the arch away, but this action does not materially affect the thin body portion of the bricks as these are protected from the scouring action on account of being raised above the lower surface of the arch, the marginal edges of the arch and the subsidiary deflecting walls formed thereby serving to deflect the fuel particles and cinders and cause them to return to the fuel bed without striking and wearing the thin portions of the bricks.

In building arches in accordance with my invention, in wide fireboxes, the arrangement of the tubes may be varied to suit different conditions, and in Figs. 5 and 6 I have shown two different arrangements of tubes one having the single tube placed in the center of the firebox, each transverse row of the bricks of the arch consisting of a pair of bricks arranged at each side of the tube, each pair being mutually interlocked, and in Fig. 6 I have shown two tubes arranged parallel with each other and each row of the bricks in the arch comprising a central pair resting at their lower ends upon the tubes and mutually interlocked at their upper ends, and a single brick arranged at

each end thereof resting at its lower end upon the tube and leaning at its upper end 65 against an adjacent side sheet.

It will now be seen that I have provided a standard arch construction which is exceedingly flexible in that arches can be built of bricks which are substantially identical 70 in form; that the arches can be made of sizes to fit substantially all widths of fireboxes and that the arches can be made of such sizes and dimensions that they will fulfill substantially any desired conditions. Further 75 75 can be built of as low weight as is consistent with the proper strength of the bricks to withstand the shocks to which they are subjected in use. Furthermore, as by my system many different sizes of arches 80 can be built by the use of one standard size and form, of brick, it is seen that the installation and maintenance of such arches upon a railroad system can be accomplished at a minimum expense, for the reason that 85 as but one number or size of brick is used it is not necessary to carry a great quantity in stock at various points where arches are built and repaired and consequently the capital outlay is relatively small. 90

As many modifications of my invention will readily suggest themselves to one skilled in the art I do not limit or confine my invention to the specific structures herein shown and described. 95

I claim:

1. A locomotive boiler firebox, its inclined, water-circulating arch-tubes and its side sheets, in combination with a refractory arch supported by said tubes and side sheets and composed of oppositely inclined interchangeable elongated bricks, each thereof having an arch-tube socket at its lower end, and an interchangeable interlock at its upper end. 100

2. A locomotive boiler firebox in combination with a refractory arch therein and composed of oppositely inclined interchangeable elongated bricks, each thereof having an arch tube socket in its lower end, and an interchangeable interlock at its upper end. 105 110

3. A locomotive boiler firebox in combination with a refractory arch therein and composed of oppositely inclined interchangeable elongated bricks, each thereof having an arch tube socket in its lower end, an interchangeable interlock at its upper end, and containing a gas mixing pocket in its under side. 115

In testimony whereof, I have hereunto set my hand, this 24th day of January, 1912, 120 in the presence of two subscribing witnesses.

CHARLES B. MOORE.
